UNITED STATES PATENT OFFICE.

FRED L. DUNLAP, OF JEFFERSON CITY, MISSOURI.

SELECTIVELY-OPERATED PUNCHING MACHINE.

Application filed November 8, 1927. Serial No. 231,929.

This invention relates to improvements in selectively operated punching machines having for an object to provide a machine especially advantageous for the use in 5 punching of card strips and like master elements used to automatically control the operation of accounting machines, automatic typewriters and kindred apparatus wherein a slideable card or strip holder is cooperatively associated with a guide device and is adapted to be automatically moved to a predetermined position for punching of the card or strip arranged therein.

It is likewise an equally important object 15 of the invention to provide a machine of the character indicated employing a plurality of appropriately indicated actuating keys adapted to be operated for causing the slideable card or strip holder to be checked or 20 temporarily stopped in its sliding movement in order to permit the punching of the card or strip carried thereby at a desired point.

Other objects of the invention will be in 25 part obvious and in part pointed out hereinafter.

In order that the invention and its mode 30 of operation may be readily understood by those skilled in the art to which it appertains, I have in the accompanying illustrative drawings and in the detailed following description based thereupon, set out one possible embodiment of the invention.

In these drawings: 35 Figure 1 is a top plan view of the improved punching machine having a part thereof removed to show the arrangement of the key carrying bars and a portion of the guide bracket for said bars broken away to show the arrangement of the relatively 40 juxtaposed vertically disposed guide rods adjacent the different juxtaposed key bars,

Figure 2 is a vertical transverse section through the machine,

Figure 3 is a fragmentary detail in longitudinal section taken on the line 3—3 of Figure 2 looking in the direction in which the arrows point, and

Figure 4 is an enlarged fragmentary detail in section through the punching mechanism of the machine.

Having more particular reference to the drawings in connection with which like characters of reference will designate corresponding parts throughout, the improved

machine may be stated to comprise a casting like body indicated in its entirety at this time by the numeral 1, said body being provided with compartments 2 and 3; the compartment 2 being adapted to be normally closed by means of a cover plate 4 secured in position through the medium of screws or other suitable fastening devices whereas the compartment 3 is adapted to be normally closed by means of a cover plate inset with respect to said compartment and received upon a rabbeted or shouldered portion 5 therein.

Arranged adjacent the normally forward side and longitudinally of the compartment 3 of the body 1 is a guide bar 6, said guide bar having appropriately arranged graduations generally indicated by the numeral 7 inscribed or otherwise presented upon a portion of the face side thereof; the inner end of this bar terminating adjacent the inner end of the compartment 2 whereas a plurality of guide ears or holders 8 are fixedly mounted upon the outer portion of said bar as is shown in the Figure 1 whereby 80 to receive and to insure proper positioning of a card or strip to be punched with the machine with respect to the punching mechanism, hereinafter more fully described. Also, it is to be noted that the longitudinally disposed guide bar 6 is provided throughout its length with a shouldered portion 9 against which the adjacent marginal portion of a card or strip to be punched by the machine, has bearing, hence, securing 85 proper relative positioning of said card or strip both during the time of its adjustment with respect to the punching mechanism and the final positioning thereof with relation to the punching mechanism immediately prior to punching of the card or strip.

Slidably mounted upon the longitudinally disposed guide bar 6 and movable longitudinally over the same is a yoke like carriage device indicated at this time by the numeral 10, said carriage having embracing engagement with respect to the guide bar and being formed with a shouldered portion upon the under face thereof corresponding with the shouldered portion 9 of the bar whereby to insure a snug slideable engagement with the same; a handle 11 being fixedly mounted upon the upper side of the carriage cap whereby to facilitate the imparting of slid-

ing movement thereto in one direction. Carried upon the under side of the slidable carriage 10 is a leg 12 having an arm 13 fixedly connected thereto as indicated at 14, 5 said arm 13 being disposed longitudinally of the casing like body 1 and extended through a suitable way 15 formed in the partition or wall 16 between the compartments 2 and 3, into the compartment 2, 10 whereat it is fixedly engaged, as at 17 with a sleeve like bearing device 18 slidably engaged with a supporting and guide rod 19 mounted in the opposite end walls of the compartment 2 and disposed longitudinally 15 thereof as is shown in the Figures 1 and 3.

That this slidable carriage 10 and the arm 13 connected thereto and slidably engaged with the guide rod 19 through the medium of the sleeve like bearing 18 may be 20 normally retained in position as is shown in the Figures 1 and 3, I attach one end of a contractile coil spring 20 to a portion of the leg 12 whereas the opposite end of said spring is fixedly connected to the outer end 25 wall of the compartment 3. By reason of the connection of this contractile coil spring 20 to the carriage 10 in the manner aforesaid, it will be understood and appreciated that said carriage will be normally yet yieldably retained in the position as is indicated in the said Figures 1 and 3.

With a view toward providing the carriage 10 with means for temporarily checking or stopping the sliding movement of the same 35 along the guide bar 6 at predetermined points whereby to permit of the punching of holes in a card or strip engaged by said carriage and arranged upon the guide bar, 6, I mount upon a suitable pivot supporting 40 bar 21 supported in the forward side and upper portion of the compartment 3 as is shown in the Figures 1 and 2, a plurality of pivotal bars generally indicated herein by the numeral 22, each of said bars having 45 the outer ends thereof formed with upstanding shanks 23 carrying appropriately designated keys 24; the inner portions of these bars 22 being each formed with offset or irregular portions 25 whereby they may be 50 arranged or extended under the longitudinally disposed supporting and guide rod 19 within said compartment 2 whereas the free and inner ends of said bars are each engaged by the upper ends of contractile coiled 55 springs generally indicated by the numeral 26, the lower ends of which are secured to the adjacent portion of the casing bottom as indicated at 27. By reason of this pivotal mounting and spring connection of the key 60 carrying bars 22, it will be understood that with depression of the respective keys 24 carried upon the shank 23 thereof, the inner ends of said bars will be raised from their normal position and when in such raised 65 position will be disposed in the path of travel

of the sleeve like bearing 18, hence affording a means for temporarily checking or stopping said element, together with the carriage 10 and the arm 13 during the time of movement of the same toward the outer end of 70 the compartment 3 under urge of the contractile coil spring 20. However, when the engaged key bar is released, the contractile coil spring 26 connected thereto will immediately return the inner end of the same 75 to its normal out of the way position as respects the sleeve like bearing 18 and at this time, the carriage 10 together with the arm 13 and said sleeve like bearing 18 are free to return to their normal position under influence of the coil spring 20.

In mounting the key carrying bars 22 within the compartment 2, it will be noted that the same are positioned in relative juxtaposed relation longitudinally of said compartment and to insure individual operation of the same without interference with one another, I arrange within said compartment 2 and over the intermediate portions of the bars 22 a substantially inverted U-shaped 85 bracket 28 passing screws or other suitable fastening devices 29 through the seat formed upon the opposite extremities thereof into engagement with adjacent portions of the casing bottom; the upper horizontal portion 90 of said bracket 28 having the upper ends of a plurality of vertically disposed and relatively juxtaposed guide rods generally designated by the numeral 30 fixedly secured therein whereas the lower ends of each of 100 the guide rods are similarly secured in a bar 31 fixedly mounted adjacent the bottom of the casing 1 and immediately below the upper and horizontal portion of said bracket 28. Thus, it will be appreciated that these 105 guide rods 30 consequently upon their individual arrangement between the various juxtaposed key carrying bars 22 will serve as means for retaining said bars in their relative individual positions so that free and 110 uninterrupted operation of the same will be at all times insured.

That the forward portions of the key carrying bars 22 may be afforded free pivotal movement at the time when they are selectively operated, I may and preferably do cut away a portion of the front wall of the compartment 2 of the casing 1 as is shown at 32, thus allowing depression of the various key carrying bars 22 to such an extent as to 115 insure the raising of the inner extremities thereof into the normal path of travel of the bearing like device 18 whereby that device may be selectively checked at a predetermined point during its sliding movement in 120 the direction hereinbefore indicated.

That a card or strip arranged upon the guide bar 6 and adjacent the ears or holders 8 may be punched subsequently to adjustment of the same upon said bar through the 130

instrumentalities of the carriage 10, the arm 13, the sleeve like bearing device 18 and a selectively adjusted key carrying bar 22, are fixedly secured the usual apertured arm 33 of an approved type of punching mechanism to the upper marginal portion of the forward wall of the compartment 3, forming said arm 33 with a substantially right angular like bracket portion 34 and passing a securing screw or screws or similar fastening devices 35 through the vertical portion of the same into engagement with said forward wall, as is shown in the Figure 4; the horizontal or upper portion of the bracket 34 being extended for a distance beyond the wall and having a guide opening formed therein and adapted to slidably receive a shank or operating rod 36 therethrough, this rod being vertically disposed with respect to the casing 1 and in substantial parallelism to the outer side or face of the forward wall of the same and slidably passed through an opening formed in the bottom of the casing 1 to a point below said casing whereat it is provided with a foot pedal or similar device 37; the upper end of said operating rod 36 being normally disposed above the operative arm 33 and formed with a right angular extension 38 carrying a punch 39 upon the lower side of the free end of the same as is shown in the Figure 4, said punch 39 being vertically aligned with respect to the punch receiving opening formed in the arm 33 so that with depression of the foot pedal 37, the rod 36 will be drawn downwardly and in so doing, will cause the punch 39 to enter the opening of the arm 33 and thereby to punch a card or strip arranged upon the shouldered longitudinal guide 6 and over the correspondingly shouldered portion 40 of said arm 33.

In operation of my improved punching machine, a card or strip to be punched is arranged upon the guide 6 under the ears 8 and adjacent the punching mechanism whereupon the handle 11 of the carriage 10 is grasped by an operator and is slid in a direction toward the compartment 3 at which time the contractile coil spring 20 engaging said carriage will be placed under tension. The carriage 10 is moved to the full extent of its slideable movement toward the compartment 2 and the previously inserted or arranged card or strip to be punched by the machine is brought into abutting engagement with it. With the machine so adjusted, it will be understood that the spring 20 will exert an urge or opposite sliding movement upon the carriage 10 and at this time, the machine operator selects and depresses one of the appropriately designated keys 24 of the key carrying bars 22, causing that particular bar 22 to be pivoted against the tension of its particular coiled spring 26 and to be moved upwardly so as to be arranged in the path of return travel of the sleeve like bear-

ing device 18. The handle 11 of the carriage 10 is now released whereupon such carriage will immediately start upon a return sliding movement under influence of the tensioned coil spring 20. However, as said carriage moves along the guide rod 19, it will engage the previously depressed key carrying bar 22 and will be temporarily checked in its sliding movement. With stopping of the carriage 10 by the selectively operated key carrying bar 22, said carriage will be arranged adjacent one of the graduations 7 inscribed upon the guide bar 6 and particularly, adjacent that graduation on said bar corresponding to the appropriately designated matter of the key 24 of said depressed key carrying bar 22. The punching mechanism is now operated whereby to punch the card following which the depressed key 24 is released and the carriage 10 is permitted to return under influence of the coil spring 20 to its normal position as is shown in the Figure 1, whereupon another card or strip may be inserted and the punching operation just described repeated; any one of the various keys 24 being selectively depressed whereby to check or to stop the return sliding movement of the carriage 10 at a predetermined point or graduation 7 upon the guide bar 6 depending upon the key actuated.

Manifestly, the construction shown is capable of considerable modification and such modification as is within the scope of my claims, I consider within the spirit of my invention.

I claim:

1. A card punching machine comprising a casing like body, a plurality of individually operable key carrying bars pivotally mounted thereon, a guide bar for retaining a card to be punched, a card setting carriage slidably mounted on the casing adapted to be checked in its sliding movement in one direction by an actuated key carrying bar, and a card punching means on said casing cooperable with said guide bar and carriage.

2. A punching machine comprising a casing like body, a plurality of individually operable key carrying bars pivotally mounted thereon, a longitudinally disposed and graduated guide bar supported on the casing, a carriage slidably mounted upon said guide adapted to be checked in its sliding movement in one direction by an actuated bar, means for returning said carriage to its normal position upon the guide, and punching means on the casing cooperable with said guide and carriage.

3. A punching machine comprising a casing having a plurality of juxtaposed compartments formed therein, a longitudinally disposed and graduated guide bar mounted on the casing adjacent one of said compartments, a carriage slidably engaged with and movable over said guide bar, a plurality of

individually operable key carrying bars pivotally mounted in the remaining compartment in relative juxtaposed relation, an arm carried by said carriage and extended into 5 and movable through said second compartment over said key carrying bar and adapted to be temporarily engaged and checked by a particularly actuated key carrying bar, punching means on said casing in proximity 10 to said guide bar and cooperable with said carriage.

4. A punching machine comprising a casting like body having a plurality of juxtaposed compartments therein, a graduated guide bar fixedly mounted adjacent the forward wall of one of said compartments and disposed longitudinally thereof, card or strip holding means upon a portion of said bar, a carriage slidably engaged with and 15 movable over the bar, one end of said bar terminating adjacent the remaining of said compartments in the casing, a guide rod fixedly mounted within said second compartment disposed longitudinally of the same 20 and in alignment with said guide bar, an arm fixedly secured to the carriage, a bearing sleeve slidably engaged with said guide rod and connected to said arm, a plurality of individually operable key carrying arms 25 mounted in relative juxtaposed relation in said second compartment, the key carrying portions of said bar being arranged without the compartment and beyond the casing, portions of said key carrying bars with de- 30 pression of the same being adapted to be arranged in the path of movement of the bearing like sleeve upon said guide rod, and punching means mounted on the casing 35

adjacent said guide bar and cooperable with said carriage. 40

5. A punching machine comprising a casting like body having a plurality of juxtaposed compartments therein, a graduated guide bar fixedly mounted adjacent the forward wall of one of said compartments and disposed longitudinally of the same, card or strip engaging and retaining ears formed upon said guide bar, a carriage engaged with and slidable over the graduated guide bar, spring means connected to said carriage 50 for returning and retaining the same in a normal position, a guide rod fixedly mounted in the remaining compartment longitudinally of the same and in substantial parallelism to said guide bar, an arm fixedly connected to the under side of said carriage and extended into said second compartment, a sleeve like bearing device secured to the free end of said arm and slidable over said guide rod, a plurality of individually operable key carrying bars pivotally mounted in the second compartment in relatively juxtaposed relation, portions of said key carrying bar, with individual depression there- 60 of being adapted to be arranged in the path of sliding movement of said sleeve like bearing device, spring means engaging each of the inner ends of said key carrying bar for retaining and returning the same to their respective normal positions, and punching 65 means mounted on the casing adjacent said guide bar and cooperable with said carriage. 70

In witness whereof I have hereunto set my hand.

FRED L. DUNLAP.
